CARL ERIC ANDERSON, OF STRATFORD, CONNECTICUT, ASSIGNEE TO THE BRYANT ELECTRIC COMPANY, OF BRIDGEPORT, CONNECTICUT, A CORPORATION OF CONNECTICUT.

ELECTRIC SWITCH.

Application filed July 15, 1924. Serial No. 726,181.

To all whom it may concern:

Be it known that I, CARL ERIC ANDERSON, a citizen of the United States of America, residing at Stratford, in the county of Fairfield and State of Connecticut, have invented certain new and useful Improvements in Electric Switches, of which the following is a specification.

My invention relates to electric switches, and particularly to switches of the push bar type. The object of my invention is to provide a switch of small dimensions, adapted for mounting in fan motor bases, canopies and the like, in which the snap switch mechanism is operated by a push and pull bar, and in which the mechanism, though of small dimensions, is capable of efficiently handling a relatively heavy current.

In the accompanying drawings—

Fig. 1 is a side elevation of a switch in which my invention is embodied in one form;

Fig. 2 is a section taken on the line of division between the insulating blocks of the switch body;

Fig. 3 is a similar view looking in the opposite direction;

Fig. 4 is a section on the line 4—4, Fig. 2; Fig. 5 is a section on the line 5—5, Fig. 1; Fig. 6 is a section through the commutator assembly unit drawn to a larger scale;

Fig. 7 is a section at right angles to Fig. 6; and

Fig. 8 is an inverted plan of the spring abutment washer.

In the form here shown the switch comprises a two-piece insulating body formed by the blocks 15 and 16, of the same external contour, but recessed on their adjacent faces to afford a switch chamber 17 and appropriate passages for the conductors, operating mechanism, etc. Against one wall of the switch chamber 17, but on opposite sides of the line of division between the blocks, rest the switch contacts 18 and 19. The latter constitute flanges offset from straps 20 and 21, engaged beneath the outer heads of tapped rivets 22 and 23, respectively passing through the blocks 15 and 16. Entering the rivets are the exterior binding screws 24

and 25 by which the lead wires are connected to the switch. Apertures 26 (Fig. 3) formed in the respective blocks permit the switch contacts 18 and 19 to enter the switch chamber 17 from the exterior ledges upon which the straps 20 and 21 are seated.

The commutator 27 by which connection is made or broken between the switch contacts 18 and 19, is struck from sheet metal and comprises a pair of contact wings 28 and 29, between which is a channel 30 for the reception of the actuator. A stem 31 projects from one margin of the commutator and is provided with a flat head 32 adapted to be passed through the slot 33 and engaged in the seat 34 formed at right angles to the slot in the abutment washer 35. A coil spring 36 is engaged between the washer 35 and the shoulders 37 on opposite sides of the stem 31. In assembled position the commutator 27 is arranged in the switch chamber 17 and its wings 28—29 engage either the contacts 18 and 19, or the wall 38 at the opposite side of the switch chamber, which forms a stop limiting the throw of the commutator. Opening to the bottom of the switch chamber is a well 39 shouldered at 40 to form a supporting ledge against which the washer 35 rests. The lower portion of the stem 31 and spring 36 extend into the well, the portion of which below the shoulder 40 is of sufficient size to accommodate the head 32 at the lower end of the stem 31 and to permit its angular play therein on the throw of the commutator.

The actuator, by means of which the commutator is shifted from circuit-closing to open-circuit position, and vice versa, comprises a sheet metal plate 41 provided with a peaked cam 42 intermediate its end guide legs 43. From one of the latter projects a threaded lug 44 by which screw connection is made with a threaded socket at one end of the stem 45 of the push and pull button 46, by which the push bar is operated. The actuator plate 41 lies in a plane substantially at right angles to that of the commutator 27, and the peaked cam 42 is engaged in the notch 30 of the commutator. A depression 47 in the block 15 accommodates the push

plate and is of sufficient length to permit its necessary rectilinear movement, while at the same time limiting the extent thereof. The margin 48 of the depression 47 is straight, and forms a guide for the straight edge of the push plate 41 which is constantly held against this margin of the depression by the effort of the spring 36 exerted through the commutator.

- 10 The stem 45 of the push plate passes through a hollow bushing 49, the head 50 of which is engaged in appropriate recesses 51 at one end of the blocks 15 and 16, while a pair of clamping nuts 52 and 53 are threaded 15 on the projecting stem of the bushing, and afford means not only for clamping the nipple in place, but also for clamping the switch in the fan base, canopy or other appropriate support. The screw connection 20 between the stem 45 of the push bar and the lug 44 of the push plate 41, permits the removal of the stem 45 and nut 53, so that the bushing 49 may be passed through a small diameter hole therein of sufficient size to 25 accommodate the bushing.

To unite the blocks and hold the switch mechanism in assembled position, any suitable means may be employed, such as a rivet or bolt. For convenience I have here illustrated a pair of bolts 54 and 55 arranged at 30 opposite corners of the switch body and piercing the blocks to engage nuts 56 seated in appropriate exterior recesses.

The operation of the switch mechanism 35 will be readily understood. In Figs. 2, 4 and 5 the switch is shown in closed-circuit position, the commutator 27 bridging the contacts 18 and 19, and the stem 45 of the actuator 41 pulled out. To open the switch 40 the actuator is shifted rectilinearly by pushing the button 46 toward the switch body. As the peaked cam 42 of the actuator plate 41 travels to the left, it depresses the commutator, thus increasing the stress of the 45 spring 36. When the peak of the cam 42 passes the plane of the commutator, the stress of the spring forces the commutator to travel rapidly down the opposite incline of the actuator, and thus throws the commutator to open-circuit position against the 50 wall 38 of the switch chamber. A reverse movement of the actuator restores the commutator to circuit-closing position.

The manufacture and assembly of the 55 switch parts is extremely simple. Thus, the commutator and washer 35 may both be struck from sheet metal, and when assembled with the coil spring 36, form a self-contained assembly unit which may be 60 handled without danger of disengagement or loss of the spring or washer. To assemble the parts the actuator plate 41 may be placed in the depression 47 of block 15, the commutator straddled on the cam edge 65 thereof, and the washer 35 forced up the

stem 31 sufficiently to permit it to be seated upon the ledge 36. The block 16 may then be placed upon and secured to the block 15 to complete the assembly of the parts.

Various modifications in details of shape 70 and construction will readily occur to those dealing with the structure which do not, however, depart from what I claim as my invention.

I claim—

1. An electric switch comprising a pair of insulating blocks recessed on their adjacent faces to form a switch chamber, switch contacts arranged in said chamber but on opposite sides of the line of division therebetween, a commutator having a throw across said switch chamber and adapted to make and break connection between said contacts, a rectilinearly movable actuator slidably confined between the adjacent faces of said blocks and having a peaked cam in slidable engagement with the commutator, together with a spring engaging the commutator and pressing the latter against the peaked cam of the actuator to cause the throw of the 80 commutator as the peak of the cam passes its point of engagement with the commutator on the displacement of the actuator.

2. An electric switch comprising a pair of insulating blocks recessed on their adjacent faces to form a switch chamber, switch contacts arranged in said chamber but on opposite sides of the line of division therebetween, a commutator having a throw across said switch chamber and adapted to make and break connection between said contacts, a rectilinearly movable actuator slidably confined between the adjacent faces of said blocks and having a peaked cam in slidable engagement with the commutator, 85 a push and pull rod detachably engaged with one end of the actuator for operating the latter, and a spring engaging the commutator to hold the latter against the cam of the actuator.

3. An electric switch comprising a pair of insulating blocks recessed on their adjacent faces to form a switch chamber, a wire terminal arranged on the outer face of each block and having an associated switch contact strap passing through the block into the switch chamber, but on opposite sides of the line of division between the blocks, a commutator arranged in the switch chamber and having a throw across the latter to make and break connection between the switch contacts, together with a rectilinearly displaceable actuator slidably engaged between the opposed faces of the blocks, and having a peaked cam engaging the commutator, 100 and a spring pressing the latter against the cam.

4. In an electric switch, a pair of insulating blocks recessed on their adjacent faces to form a switch chamber, one of said 105

blocks having a shallow depression extending beyond opposite ends of the switch chamber, a flat metal rectilinearly movable actuator accommodated in said depression and having a peaked cam traversing the switch chamber, together with a commutator arranged in said switch chamber substan-

tially at right angles to the actuator, and a spring pressing said commutator into engagement with the peaked cam.

10

In testimony whereof I have signed my name to this specification.

CARL ERIC ANDERSON.
